Attorney.

UNITED STATES PATENT OFFICE.

JOHN WEISBROD, OF NEW YORK, N. Y., ASSIGNOR OF ONE-HALF TO CHARLES O. BOYER, OF BROOKLYN, NEW YORK, AND ONE-HALF TO FERDINAND KUSTER, OF NEW YORK, N. Y.

BOOKBINDER.

No. 892,200.

Specification of Letters Patent.

Patented June 30, 1908.

Application filed January 22, 1908. Serial No. 412,054.

To all whom it may concern:

Be it known that I, JOHN WEISBROD, a citizen of the United States, residing at New York city, Manhattan borough, county and 5 State of New York, have invented certain new and useful Improvements in Bookbinders, of which the following is a clear, full, and exact description.

This invention relates to book-binders, one 10 of the objects being to provide a device which is simple in construction and effective in operation.

A further object of my improved book-binder is to provide a laterally adjustable 15 frame whereby a book of any desired thickness can be built up by adding more leaves. The elements which go to form my improved book-binder are constituted to obviate the necessity of perforating the leaves of the 20 book and yet to hold the leaves firmly in position.

Further advantages will be hereinafter presented.

To these and other ends which will herein- 25 after appear, my invention comprises the novel features of improvement and combination and arrangement of parts which I will now proceed to describe and finally claim, reference being had to the accompanying 30 drawings, forming part hereof, wherein—

Figure 1 illustrates a perspective view of my improved book-binder, the leaves being removed; Fig. 2 is a detail top-plan view of my improved book-binder, the cover being 35 removed and a portion of the leaves shown; Fig. 3 is a detail sectional view, taken on a line *a*—*a* in Fig. 2, and shows the retaining bars for the leaves in position; Fig. 4 is a perspective view, broken off, of the retaining 40 bar and shows the manner of retaining the leaves; Fig. 5 is an enlarged cross-sectional detail view of the locking-bar and spring carried thereby; Fig. 6 is an enlarged fragmentary sectional detail plan view of my improved 45 adjustable frame.

Referring now to the drawings, particularly to Fig. 1, my improved book-binder comprises the end-members 1 and 2, said end members being composed of the stationary 50 members 3 and 4 (Fig. 2) upon which are mounted laterally adjustable plates 5, 6, 7, and 8. A separator 9, of wood or other material to which the stationary members 3 and 4 are suitably secured, determines the 55 width of the book. The end members 1 and

2 and the plates 5, 6, 7 and 8 thereon, together with the separator 9, form the frame or binder for the book. A cover 10 is secured to the separator in the usual manner.

As shown in Fig. 6, the adjustable plates 5, 6, 7 and 8 are secured to the stationary members 3 and 4 by the thumb-nuts 11, which engage threaded studs 12 carried by the members 3 and 4. The plates 5, 6, 7 and 8 are provided with slots 13 through which 60 the studs 12 pass. To steady the plates 5, 6, 7 and 8, I have, in this instance, employed steady pins 14, which project from the members 3 and 4 and enter the slots 13 (see Fig. 1). To the upper end of the plate 5 I 65 pivotally mount a locking-bar 15, as at 16. Near the bottom of the under plates 6 and 8, I secure the stationary reach-bar 17 (see Fig. 3). The retaining elements for the leaves comprise the bars 18, around which 70 are folded a plurality of leaves 19 to form the book (see Fig. 4), each folded sheet forming two leaves. I can use as many of these 75 groups of leaves as desired. After having made as many groups of leaves as I desire, 80 and in the manner described, I place the groups one upon the other between the end frames 1 and 2, the adjustable plates 5, 6, 7 and 8 being provided with an inwardly projecting flange 20 which acts to keep the bars 85 18 from slipping outwardly longitudinally of the book. The bars 18 are a little shorter than the distance between the end frames 1 and 2 which permits of the easy insertion of the bars. The difference between the length 90 of the said bars and the width between the members 1 and 2 will not be enough to permit of side lashing of the bars 18 and groups of leaves thereon. After having inserted the bars, the locking-bar 15 is closed and a pin 95 21 is, in this instance, used to hold the bar 15 closed as shown in Figs. 1 and 2.

To hold the groups down, and to press them firmly together, I mount on the under- 100 side of the locking-bar 15 an auxiliary locking element, comprising a leaf-spring 22, which, when the bar 15 is locked, presses upon the top group of leaves. The spring 22 also compensates for the space of a group, should said group be removed for any purpose. In other words I am able to take out 105 a group of leaves or to add a group without affecting the stability of the book, as the said spring 15 will compress, if I add a group, or expand if a group is removed. Therefore, 110

under these two circumstances, the said spring will always act to firmly press the groups downward and together.

If I desire to increase the capacity of the binder to an extent greater than can be accomplished by adding one or two groups of leaves as has been described, I loosen the thumb-nuts 11 and draw the adjustable plates 5 and 7 upwardly and push the plates 6 and 8 downwardly to the desired extent, and then tighten the thumb-nuts 11, whereby the end frames 1 and 3 are greatly increased in lateral width. By this means I am able to add several more groups of leaves to the book. The flexible portion 22^a of the cover 10 permits the cover to accommodate itself to the increased thickness of the book.

Having now described my invention, what I claim and desire to secure by Letters Patent is:

1. In a book-binder, a binding-frame provided at the ends thereof with laterally adjustable members, and bars carried by said

members, one of said bars constituting a locking element.

2. In a book-binder, a binding-frame, laterally adjustable end members carried by said frame, a plurality of independent removable retaining bars, adapted to hold leaves, carried by said frame, and means adapted to hold said bars and the leaves carried thereby, in said frame.

3. A book-binder, comprising a frame, composed of a separator, end members carried by said separator, laterally adjustable plates carried by said end members, a reach-bar carried by the lower plates, a pivotally mounted locking-bar carried by the upper plates, and an auxiliary locking element carried by said locking-bar.

Signed at New York city, this 20 day of January 1908.

JOHN WEISBROD.
